UNITED STATES PATENT OFFICE.

JOHN D. BLOOM, OF NEW YORK, N. Y.

BUTTER-CUTTER.

SPECIFICATION forming part of Letters Patent No. 759,658, dated May 10, 1904.

Application filed September 9, 1903. Serial No. 172,441. (No model.)

To all whom it may concern:

Be it known that I, JOHN D. BLOOM, a citizen of the United States, and a resident of New York city, in the county of New York and 5 State of New York, have invented certain new and useful Improvements in Butter-Cutters, of which the following is a specification.

The present invention relates to machines for cutting cubes or squares of butter, and 10 while readily adaptable for embodiment in constructions for cutting any desired sizes of cubes or squares is more particularly designed for the production of a comparatively large number of the same and of small size for use 15 in restaurants and similar establishments where it is generally necessary to have on hand a considerable supply of butter in such condition.

The more prominent objects of the invention 20 are the simplification and consequent cheapening of the machine, increased convenience of handling and efficiency of the latter, and facility for maintaining the same in a cleanly condition, a highly-important consideration 25 in this class of constructions.

With the above and other purposes in view the improved butter-cutter comprises a base having a section for supporting a frame adapted 30 for the reception of a charge of butter and equipped with wires disposed for dividing the butter into blocks or cubes of the desired size, the other section of the base being adapted to serve, in connection with the frame, for contributing to the discharge of the butter in 35 the condition stated.

There are other important features connected with the machine which, in addition to those alluded to, are clearly set forth in the subsequent detailed description.

In the accompanying drawings, forming 40 part of this specification, Figure 1 is a perspective view of a butter-cutting machine embodying my invention, the butter-carrying frame and its follower being represented in a 45 position suitable for the conversion of the butter into cubes or squares. Fig. 2 is a transverse section of the machine as disclosed in Fig. 1. Fig. 3 is an inverted plan view of a part of the cutter-frame. Fig. 4 is a view 50 somewhat similar to Fig. 2, but illustrating a

modification. Fig. 5 is a central longitudinal sectional view of the base of the machine, said base being represented on a somewhat smaller scale than it is shown in Figs. 1 and 2.

Similar reference characters are employed 55 to designate corresponding parts in the several figures of the drawings wherein they occur.

Referring now more particularly to Figs. 1 to 3, inclusive, the base A of the machine is 60 presented by a single piece, preferably of wood, and is of rectangular configuration. This base is provided at its sides with upper ledges α , which extend throughout the length of the base. At its front the base has secured 65 an upper stop α' , transversely disposed, as indicated in Fig. 1, and having its ends with upper bevels for the purpose of avoiding objectionable abrupt angles at this point. At its rear the base is imperforate for constituting 70 the platform or surface A'. A rectangular opening A² of relatively ample dimensions is located in the forward part of the base. A rectangular frame B of open character is adapted to slidingly fit between the ledges α and is 75 beveled at its lower side to form an undercut shoulder b , extending along all four sides of the frame. Secured in the lower part of the frame are plates b' , which are angular to bear both against the contiguous vertical side of 80 the frame and also the adjacent beveled shoulder b' thereof. From the inclined portions of these plates project the heads and parts of the shanks of a series of screws b'' , the plates having shallow channels which coincide with 85 kerfs b^3 in the bottom surface of the frame. A steel wire c of fine gage is secured to the end screw b'' of one of the four series of the same and is then extended across the frame-bottom and led around the corresponding screw at the 90 opposite side, then around the screw next adjacent, and again brought across the frame, where it is further passed around two screws, these operations being repeated until the wire finally passes around an end screw and is 95 wound upon a screw C', bearing in the frame and serving for the tightening of the wire. A similar arrangement of wire turns and passes across at a right angle to that of the wire previously mentioned, and thus results in equip- 100

ping the bottom of the frame B with wires capable of dividing the butter into the required forms. A follower C of flat plate-like character is adapted to snugly fit within the frame 5 B and is provided with an upper handle C', by which it may be removed from or applied in position and be properly manipulated.

In practice the base can be so supported that the opening A² will be immediately over 10 a crock or other receptacle in which it is desired to hold the butter after it has been cut. The frame B is moved back upon the surface A', and with the follower C being removed 15 butter can be introduced into the frame and compressed to fill the same. The frame is then slid along the base until its wire cutting-surface will be in registration above the opening A² in the base, this being accomplished without particular adjustment by the frame 20 contacting with the stop a', which is located with special reference to positioning the frame in the manner referred to. The follower C will then be applied and operated to force the butter through the bottom of the frame, the 25 wire c dividing as it passes, the resulting cubes or squares dropping into the crock or other receptacle. The beveled shoulders at the under side of the frame B, together with the peculiar angular character of the plates b', enables 30 the frame to be slid back and forth without liability of binding between the guides, and, furthermore, provides an efficient means for the connection of the wires without involving any sharp bends around the edges of 35 the frame B.

From the foregoing description it will be clear that a comparatively large number of cubes or squares can be formed at each operation and repeated as often as may be required 40 with convenience and dispatch.

I do not desire to be understood as limiting myself to the precise details shown and described, but reserve the right to all modifications that may be within the scope of my in-

vention. For instance, as illustrated in Fig. 4, 45 the base A³ may be minus the side ledges and instead of the opening A² in its forward part may have instead at such point a raised rectangular projection or block A⁴, so that after the frame B has been filled upon the rear 50 platform A' such frame can be raised and inverted and then placed upon the projection A⁴, and upon being forced down such projection will force the butter upward through the wires in the form of the cubes desired. 55

Having now described my invention, what I claim as new, and desire to secure by Letters Patent, is—

1. In a butter-cutting machine, the combination with a base having an imperforate section and a portion adapted for the discharge of the butter, of a frame provided with lower beveled edges, plates secured to said edges, and cutting-wires connected to said plates and spanning the frame. 60

2. In a butter-cutting machine, the combination with a base provided with side guide-ledges, and an imperforate section and ample opening between the ledges, of a frame slideable between said ledges, and equipped with 70 lower cutting-wires, and a follower adapted for snugly fitting within said frame.

3. In a butter-cutting machine, the combination with a base provided with guide-ledges and an imperforate section and ample opening 75 between the ledges, of a frame provided with lower beveled edges, angular plates bearing both against the bevelled edges, and vertical sides of the frame, and cutting-wires connected to said plates and spanning the frame. 80

Signed at New York, in the county of New York and State of New York, this 5th day of September, A. D. 1903.
